US00D751552S

(12) **United States Design Patent**
Osterhout(10) **Patent No.:** **US D751,552 S**
(45) **Date of Patent:** **** Mar. 15, 2016**(54) **COMPUTER GLASSES**(71) Applicant: **Osterhout Group, Inc.**, San Francisco, CA (US)(72) Inventor: **Ralph F. Osterhout**, San Francisco, CA (US)(73) Assignee: **Osterhout Group, Inc.**, San Francisco, CA (US)(***) Term: **14 Years**(21) Appl. No.: **29/513,496**(22) Filed: **Dec. 31, 2014**(51) LOC (10) Cl. **14-02**

(52) U.S. Cl.

USPC .... **D14/372**(58) **Field of Classification Search**

USPC D14/372, 496, 432, 371, 125, 126, 129, D14/299; D16/300-342; 351/158, 153, 144; 345/7-9, 905; 455/344; 348/115, 53, 348/121, 739

Primary Examiner — Austin Murphy(74) *Attorney, Agent, or Firm* — GTC Law Group PC & Affiliates(57) **CLAIM**

The ornamental design for computer glasses, as shown and described.

DESCRIPTION

FIG. 1 is a front top perspective view of an embodiment of the new design;

FIG. 2 is a front view thereof;

FIG. 3 is a rear view thereof;

FIG. 4 is a side view thereof;

FIG. 5 is a side view thereof;

FIG. 6 is a top view thereof; and,

FIG. 7 is a bottom view thereof.

The broken lines in FIGS. 1-7 are for environmental purposes only and form no part of the claimed design.

1 Claim, 5 Drawing Sheets# US D751,552 S
